UNITED STATES PATENT OFFICE

98,631

DESIGN FOR A WATER HEATER CABINET

Ellis H. Wilkinson, Pottstown, Pa.

Application June 28, 1935, Serial No. 57,452

Term of patent 14 years

To all whom it may concern:

Be it known that I, Ellis H. Wilkinson, a citizen of the United States, residing in Pottstown, Pennsylvania, have invented the new, original, and ornamental Design for a Water Heater Cabinet, of which the following is a specification, reference being had to the accompanying drawing, forming part thereof, in which:

Fig. 1 is a top plan view; and
Fig. 2 is a view in front elevation of the water heater cabinet, showing my new design.

I claim:
The ornamental design for a water heater cabinet, substantially as shown.

ELLIS H. WILKINSON.
